[57] CLAIM

The ornamental design for a hot tub cover bracket, as shown and described.

DESCRIPTION

FIG. 1 is a perspective view of a hot tub cover bracket showing my new design;
FIG. 2 is a left side elevational view, the right side elevational view being a mirror image thereof;
FIG. 3 is a front elevational view;
FIG. 4 is a rear elevational view; and,
FIG. 5 is a bottom plan view.
